UNITED STATES PATENT OFFICE.

WILLIAM A. BUTLER, OF PORTSMOUTH, VIRGINIA, ASSIGNOR OF ONE-HALF TO
WILLIAM J. BEALE, OF NORFOLK, VIRGINIA.

TIE-PLATE AND RAIL-FASTENER.

1,392,398.

Specification of Letters Patent.

Patented Oct. 4, 1921.

Application filed May 23, 1921. Serial No. 471,902.

To all whom it may concern:

Be it known that I, WILLIAM A. BUTLER, a citizen of the United States, residing at Portsmouth, in the county of Norfolk and State of Virginia, have invented certain new and useful Improvements in Tie-Plates and Rail-Fasteners, of which the following is a specification.

This invention relates to means for connecting railroad rails to ties, and for bracing the rails when necessary or desirable, and the primary object of the invention is to provide a novel tie plate for forming a seat for the rails to prevent undue wear or injury to the ties, and a novel fastener and brace associated with the tie plates for effectively holding the rails against displacement or creeping.

Another object of the invention is to provide a tie plate having struck in teeth formed in the upper and lower surfaces thereof, the tie plate having slots bisecting the teeth, and fasteners slidably associated with the plate having locking teeth formed 25 on their upper surfaces for engaging the teeth on the lower surface of the plate, and fastening bolts carried by the fastening members and slidably mounted in said slots, the heads of the bolts having teeth formed 30 thereon arranged to engage the teeth formed on the lower surface of the tie plate.

A further object of the invention is to provide a novel type of brace for use in connection with the tie plate including a 35 base member for engaging the teeth formed on the tie plate, and an upwardly inclined body portion for engaging the web and ball of the rails.

A still further object is to provide a novel 40 means for connecting railroad rails to ties, and for protecting ties of the above character, which is durable and efficient in use, and which can be manufactured and placed upon the market and incorporated with ties of 45 any preferred type, at a minimum cost.

With these and other objects in view, the invention consists in the novel construction, arrangement and formation of parts, as will be hereinafter more specifically described, 50 claimed and illustrated in the accompanying drawings, forming a part of this specification, in which drawings:

Figure 1 is a plan view of a tie, showing the improved tie plates and fasteners incorporated therewith, portions of the fas-

teners being shown in section on one end of the tie.

Fig. 2 is a side elevation of a tie showing the improved tie plate and fasteners incorporated therewith, one of the tie plates and 60 its rail fastener being shown in section.

Fig. 3 is a transverse section taken on the line 3—3 of Fig. 2.

Fig. 4 is a plan view of a tie showing a slightly modified form of my tie plate incorporated therewith, one of the fastening members associated with one of the tie plates being shown in section.

Fig. 5 is an enlarged fragmentary section taken on the line 5—5 of Fig. 4.

Fig. 6 is a detail perspective view of a fastener, which is adapted to be utilized with the tie plate, and

Fig. 7 is a detail perspective view of one of the brace members, which also can be 75 utilized with the tie plate.

Referring to the drawings in detail, wherein similar reference characters designate corresponding parts throughout the several views, the letters A and B indicate 80 respectively a tie plate and fastener, which can be effectively used with concrete ties, the tie being designated in Figs. 1 to 3 by the letter C.

While I have shown the tie C of concrete, 85 it is to be understood that the tie plate A and fasteners B can be effectively used with other types of ties, and in fact I have shown in Figs. 4 and 5 of the drawings, a slightly modified form of tie plate designated by 90 the letter D which can be effectively used with wooden ties, which are designated by the letter E.

The tie C can be formed in any preferred manner, and as shown includes the body 10, 95 which can be strengthened if so desired, with longitudinally extending rods or brace wires. The tie C is adapted to receive the usual type of rails 11, and the tie plates A are disposed between the rails and the tie. 100

Directly below the tie plates A, the upper surface of the tie is provided with grooves or ways 12, for a purpose which will be hereinafter more fully described. These ways 12 can extend beyond the tie plates A 105 if so desired. The tie plates A are preferably formed of metal of the desired thickness, and can be provided with openings 12, adjacent to their corners, for the reception of bolts 13, which extend through the tie C. 110

The upper ends of these bolts are adapted to receive suitable nuts 14, which can be of the castle type, if so desired. The tie plates A, as shown, are provided with struck in 5 teeth 15, which form corrugations both on the upper and lower surfaces thereof.

These struck in teeth form corrugations both in the upper and lower surface of the tie plate A as stated and form a guide way 10 for the heads 16 of bolts 17, which are utilized for holding the rail fasteners B in position, as will be hereinafter more fully described. As shown the corrugations or teeth on the upper surface of the tie plate 15 A project above the plane of the tie plate, but if so desired, the same may extend flush with the upper surface of the tie plate. Inwardly extending slots 18 are formed in the opposite side edges of the tie plates, and bisect 20 the struck in tooth portions 15 of the tie plates, and these slots 18 form guide ways for receiving the bolts 17.

The rail fasteners B each include a body 20, the lower surface of which is provided 25 with transversely extending teeth or corrugations 21' which are adapted to engage the corrugations or teeth formed on or struck out from the upper surface of the tie plates A. The inner side edges of the body portions 30 of the fasteners B are provided with upwardly projecting lugs 21, which are adapted to engage the upper surface of the base flanges of the rails 11. The inner side edges of the body portions 20 of the rail 35 fasteners B below the lugs 21 are provided with abrupt shoulders 22, which are adapted to engage the side edges of the base flanges of the rails 11. These abrupt shoulders 22 form means for preventing 40 spreading and twisting of the rails, while the lugs 21 prevent tilting of the rails. The body portions 20 of the rail fasteners B are provided with openings 23, which are in direct alinement with the slots 18 formed 45 in the tie plates, and these openings are adapted to slidably receive the bolts 17. The upper ends of the bolts 17 are adapted to receive nuts 25, which can be of the castle type if so desired. These nuts 25 form 50 means for holding the rail fasteners in position on the tie plates in relation to the base flanges of the rails 11. It can be seen that by providing the struck out teeth or corrugations, movement of the rail fasteners 55 in relation to the tie plates A or the rails 11 is absolutely precluded. The bolts 17 are slidably mounted in the slots 18 to permit adjustment of the rail fasteners toward or away from the base flanges of the rails. 60 In use of the improved tie plates and fasteners, the plates are arranged on the upper surface of the ties, and are held in position by the bolts 13. The rails 11 are then laid on the upper surface of the plates, after 65 which the bolts 17 are placed in the opening

23 of the rail fasteners, and the bolts are then slid into the slots 18. The fasteners are then moved into operative position in relation to the base flanges of the rails, after which the nuts are tightened which bring 70 the corrugations or toothed portion 21' of the body portion 20 of the rail fasteners B into engagement with the teeth or corrugations formed on the upper surface of the tie plates A.

It is preferred that the heads 16 of the bolts 17 also be provided with corrugations 26 so as to engage the corrugations or teeth formed on the lower surface of the tie plates A. This forms a second means for absolutely precluding movement of the fasteners in relation to the tie plates A and the rails 11. While I have shown four bolts 13 for connecting each of the tie plates to the tie C, I do not limit myself to this exact number of bolts, as it can be readily seen that more or less bolts can be utilized for holding the tie plates in position.

In Figs. 4 and 5 is shown a tie plate D which is particularly adaptable for use with 90 wooden ties E, but it is to be understood that the tie plate D is susceptible of use with other types of ties.

As shown the tie E is of the ordinary form, with the exception that the upper 95 surface thereof adjacent to its opposite ends is provided with grooves or guide ways 30, which are out of alinement with each other, and which lie on opposite sides of the longitudinal axis of the tie. This tie plate D 100 is constructed exactly like the tie plate A, with the exception that only the opposite diagonal corners thereof are provided with openings 31 instead of all four corners thereof. The provision of only two openings in the tie plate D eliminates the necessity of making a plurality of openings in the tie E, and as shown each end of the tie is only provided with two openings for the reception of the fastening bolts 32. The arrangement of the fastening bolts 32 at the opposite diagonal corners of the tie plates D absolutely precludes twisting movement of the plates on the tie. It can be seen that in this form of tie plate, the teeth portions 110 thereof, which are designated by the numeral 33, and the slotted portions thereof designated by the numeral 34, are arranged on the opposite sides of the longitudinal center of the tie plate and directly over the 115 guide ways 30 formed in the upper surface of the tie E. Thus the fasteners B in this instance, engage the rails at points out of transverse alinement, which also prevents 120 spreading and twisting movement of the rails. Otherwise the association of the fasteners B with the tie plates D is exactly the same as the means of associating the fasteners B with the tie plates A.

In some instances, it is desirable to utilize 130

brace members in connection with the tie plates, such as on curved tracks or the like, and to conform with these instances, brace members F are provided. These brace members F include body portions 35, which are provided with openings 36 for receiving the fastening bolts 17. The lower surface of the body portions 35 is provided with corrugations 37 for engaging the corrugations or 10 teeth formed on the upper surface of the tie plates. The inner transverse edges of the body portions 35 of the braces F are provided with inwardly and upwardly extending transversely curved arms 38, which are 15 adapted to overlie and engage the base flanges of the rails. The inner surfaces of these arms 38 abut against the webs of the rails and engage under the balls thereof. Thus it can be seen that the same forms an 20 effective brace for the rails.

It is to be of course understood that the brace members F are to be associated with the tie plates exactly in the same manner as the fasteners B.

25 From the foregoing description, it can be seen that a novel form of a tie and fastener has been provided, which will effectively hold the rails in position against lateral shifting movement, and protect the ties 30 against undue wear by the contacting of the rails therewith.

Changes in details may be made without departing from the spirit or scope of this invention.

35 I claim:

1. In a tie plate and rail fastener, a rectangular shaped tie plate arranged to fit upon the upper surface of the tie and adapted to receive a railroad rail, the opposite side edges of the plate having inwardly extending slots formed therein, and struck in teeth formed in the upper and lower surfaces of the plate on each side of the slots, members adjustable over the 40 upper surface of the tie plate arranged to engage the rail, teeth formed on the lower

surface of the member arranged to engage the teeth formed on the upper surface of the tie plate, bolts carried by the member slidably mounted in the slots, heads formed 50 on the lower ends of the bolts, corrugations formed on said bolt heads arranged to engage the teeth formed on the lower surface of the plate, and nuts carried by the bolts arranged to frictionally engage the upper 55 surface of said members.

2. The combination with a railroad tie having guide grooves formed in the upper surface thereof adjacent to its opposite ends, of tie plates fitted on the upper surface of 60 the tie adjacent to its ends, the tie plates having inwardly extending slots formed in the opposite sides edges thereof arranged in alinement with the guide grooves, guide ways formed in the lower surface of the tie 65 plates arranged to aline with the grooves, and being of substantially the same width as the grooves, struck in teeth formed on the tie plates in said guide ways, teeth formed on the upper surface of the plates, 70 members slidably carried by the top surface of the plates arranged for movement toward and away from a rail, bolts carried by the members slidably mounted in the slots, heads formed on the bolts fitted in 75 the grooves and guide ways formed on the plates and arranged to engage the teeth in said guide ways, means for holding the bolts in position, and teeth formed on the lower surface of the members arranged to engage 80 the teeth formed on the upper surface of the tie plates.

3. A tie plate comprising a flat substantially rectangular body having guide ways struck up from the lower surface thereof, 85 the guide ways having inwardly extending slots formed therein, the plate having bolt receiving openings formed therein adjacent to the corners thereof, and teeth struck up in said guide ways forming corrugations in 90 the upper and lower surfaces of the plate.

WILLIAM A. BUTLER.
